STEAM-DISCHARGING PRESSING IRON

Fred A. Miller, St. Johns, Mo., assignor to Roland
M. Klemme, St. Louis, Mo.

Application August 17, 1939, Serial No. 290,541

6 Claims. (Cl. 38—77)

This invention relates generally to pressing irons and more specifically to pressing irons of the steaming type which include water reservoirs within the bodies of the pressing irons and are provided with heat-producing means which convert water in the reservoirs into steam for discharge from the irons at, or adjacent to, the bases thereof, the predominant object of the invention being to provide a pressing iron of the type mentioned which, because of its improved and unique construction and arrangement, is capable of economical production and efficient operation in use.

Fig. 1 is a vertical section of the improved pressing iron, portions thereof being broken away to conserve space.

Fig. 2 is a fragmentary, inverted plan view of the base of the iron illustrating the steam-discharge orifice and the steam-distributing grooves associated therewith.

Fig. 3 is a fragmentary horizontal section taken on line 3—3 of Fig. 1.

Fig. 4 is a fragmentary vertical section taken on line 4—4 of Fig. 1, a heat conductor bar hereinafter described being omitted.

Fig. 5 is a vertical section taken on line 5—5 of Fig. 1.

Fig. 6 is a vertical section taken on line 6—6 of Fig. 1.

Fig. 7 is a fragmentary horizontal section on line 7—7 of Fig. 1.

In the drawings, wherein is shown for the purpose of illustration, merely, one embodiment of the invention, A designates the improved pressing iron generally. The iron A includes a base portion which is in the form of a plate 1, said base plate being of conventional shape and being of substantial thickness as shown in Figs. 1, 4, 5, and 6. The plate 1 has formed therein, at a point adjacent to its forward end, a steam-discharge orifice 2 which is screwthreaded throughout most of its length, said steam-discharge orifice leading into an assembly of steam distributing grooves formed in the bottom face of the plate 1 which includes a groove 3 extended longitudinally of the plate 1 and a pair of divergent and slightly curved grooves 4 which communicate with the longitudinal groove 3 at the location of the steam-discharging orifice 2 (Fig. 2). The plate 1 is provided also with a cavity 5 formed in its upper face which receives a suitable electrical heating unit 6 that serves a purpose to be hereinafter set forth, said cavity 5 at the rear portion of the plate 1 being deeper

than the remainder of the cavity as indicated at 5' in Fig. 1.

The body 7 of the improved iron is in the form of an integral, one piece structure, having a bottom wall 8 from which an upstanding, marginal wall 8' extends. The front portion of the body 7 of the iron is inclined upwardly and rearwardly from the lower edge of said front portion to a substantial degree as shown in Fig. 1, while the opposed side portions of said body are inclined upwardly and inwardly to a lesser degree as shown in Figs. 5 and 6, and the rear portions thereof are substantially vertical. The lower face of the body rests on the top face of the plate 1 and said body 7 is positioned with respect to said plate 1 by means of a plurality of dowels 7' which are received in recesses formed in the body and base plate, respectively, as shown in Figs. 1, 5 and 6. Within the body 7 of the iron a reservoir 9 is formed which is adapted to receive water, said reservoir being defined by the bottom wall of the body and the upstanding marginal wall thereof.

The forward portion of the body 7 of the iron is solid, as indicated at 10 in Fig. 3, and formed in this solid portion and extended from the top of the body to the bottom thereof is an elongated opening 11, there being an annular flange 12 (Fig. 1) located adjacent to the top of the opening 11 which extends inwardly from the wall thereof to provide the opening 11 with an opening portion 11' of reduced diameter. Disposed in the opening 11 and extended through the reduced opening portion 11' is a tubular element 13 which is provided with screwthreaded portions at its opposite ends. The lower screwthreaded portion of the tubular element 13 is screwed into the screwthreaded portion of the steam-discharge orifice 2 as shown in Fig. 1, while the upper screwthreaded portion of said tubular element receives a nut 14 which is screwed against a washer 15 which is interposed between said nut and the top face of the flange 12 and is preferably formed of asbestos or other suitable heat-resisting material. The tubular element 13 performs a dual function in that it serves as a bolt for securing the body 7 of the iron to the base plate 1 thereof, and, also, said tubular element acts, in a manner to be hereinafter explained, to conduct steam to the discharge orifice 2 in the base plate 1 of the iron. In addition to the means for attaching the body 7 of the iron to the base plate 1 thereof provided by the tubular element 13 a pair of bolts 16 are provided at the rear portion

of the iron for securing said body and base plate together as shown in Fig. 7.

The recess 5 formed in the top face of the base plate 1 of the iron, and the heat-producing element 6 disposed in said recess correspond generally to the shape in plan of the base plate of the iron, and arranged in contact with the heat-producing unit 6 is a metal plate 17 which is shaped in accordance with the heat-producing unit. This metal plate has riveted, or otherwise secured thereto, an elongated conductor bar 18 which is preferably formed of copper, or other good heat-conducting material. The conductor bar 18 is disposed in a recess 19 formed in the bottom wall 8 of the body 7 of the iron, as shown in Figs. 1, 5 and 6. The conductor bar 18, adjacent to its forward end, is provided with an opening 18' formed therethrough through which the tubular element 13 extends, said opening 18' being of substantially the same diameter as the tubular element so that close contact will be produced between the wall of the opening and the outer face of the tubular element.

At the rear end of the heat producing unit 6 an electrical conducting strip 20 is mechanically and electrically connected thereto, this conductor strip being mechanically and electrically connected also to the lower ends of a pair of bolts 21 (only one thereof being shown in Fig. 1) which extend through a suitable insulator block 22. At their upper ends the bolts 21 have mechanically and electrically connected thereto in an obvious manner a conductor 23 which conducts electrical energy from a source of supply to the heat-producing unit 6 by way of the bolts 21 and the conductor strip 20.

At its top the body 7 of the iron is closed by a cover plate 24 which corresponds in plan to the shape of the top of the body. The cover plate is secured to the top of the body 7 of the iron by means of screws or other suitable fastening elements 25, and to provide a fluid-tight joint between the cover plate and the top edge of the body of the iron a gasket 26 formed of asbestos, or other heat-resisting material, is interposed therebetween. The cover plate 24 has formed thereon an upstanding steam dome 27 which preferably is shaped as shown in Fig. 1, said steam dome having formed therein a dividing wall 28 which provides within the steam dome an independent steam passageway 29 which communicates at its upper end with the interior of the steam dome and at its lower end with the upper end of the opening 11. The cover plate 24 is provided with an emergency pressure outlet 30 which is normally sealed by a frangible disk 31, said disk being capable of resisting pressure within the reservoir up to a predetermined point and being adapted to rupture when that predetermined pressure is exceeded to release the excessive pressure.

The iron A is provided with a handle 32 which is made of material characterized by being a non-conductor of heat, and for this purpose it has been found that a composition made up of Bakelite and asbestos serves very well. The handle 32 is secured to the body of the iron through the instrumentality of a bracket 33, which is secured to the handle by a screw or other suitable fastening device 34, as shown in Fig. 1, and is secured by screws, or other suitable fastening devices 35, to the cover plate 24, as shown in

the same view. The fastening devices 35 serve also to secure to the cover plate 24 a shield 36, which preferably, though not necessarily, is formed from sheet metal. This shield includes a top wall which overlies the top plate 24 of the iron, and a downwardly extended flange portion 36' which embraces the upper portion of the body 1 of the iron as shown in Fig. 1, the top wall of the shield being provided with an opening through which the steam dome 27 and the handle bracket 33 extend. In addition to being secured to the top plate 24 of the iron by the fastening elements 35, the shield 36 is secured also to the rear portion of the handle 32 by screws or other suitable fastening devices 37, one of which is shown in Fig. 1.

In order to prevent such splashing of the water in the reservoir 9 as would cause water to pass into the steam dome a plurality of spaced baffles 20 38 may, if desired, be arranged within the forward portion of the reservoir, as shown in Figs. 1 and 3. These baffles may be formed from sections of resilient sheet metal which are introduced in place in the reservoir in a bowed condition, as shown in Fig. 3, so that the tendency of the baffles to straighten out will cause the opposite side edges of the baffles to frictionally grip the walls of the reservoir and thus retain the 25 baffles in place. The baffles may be provided with apertures 39 through which steam may pass, and also steam may pass between the edges of the baffles and the walls of the reservoirs, as the joints between these parts would not be fluid-tight. 30 35 Also, a similar baffle 40 may be arranged in like manner in the lower portion of the steam dome 21 as shown in Figs. 1 and 5, this baffle also being arranged in place in a bowed condition so that it will be retained in place, and being provided with 40 one or more apertures 40' for passage of steam.

one or more apertures 40 for passage of steam. The cover plate 24 of the iron is provided with a portion 24' that extends through an opening formed through the shield 36 and is provided with an inlet opening 41 through which water may be introduced into the reservoir 9 (Fig. 6). The inlet opening 41 is normally sealed by a cap 42 which is formed of Bakelite or other suitable heat-resisting material, said cap including as an integral part thereof a flanged sleeve 43 which is externally screwthreaded and is adapted to be screwed into the screwthreaded upper portion of the inlet opening 41. The sleeve 43 is preferably formed of metal which is characterized by the ability to resist corrosion and because the upper portion of the cap 42 is formed of material which is a nonconductor of heat the danger that a person will receive burns in removing the cap is rendered quite remote.

Operation

In the use of the improved pressing iron disclosed herein water is introduced into the reservoir 9 through the inlet opening 11 and electrical connection is made between the conductor 23 and a source of electrical energy. This will result in the heat-producing unit 6 giving off heat which will heat the base plate of the iron and will heat the walls of the reservoir so as to convert the water therein into steam. The steam so produced will pass upwardly into the steam dome 27 and will move downwardly through the steam passageway 29 to the opening 11, said steam passing downwardly through the tubular ele-

ment 13 to the steam-discharge orifice 2 in the base plate 1 of the iron from which the steam is discharged into the steam distributing grooves 3 and 4.

When the improved iron is in operation the plate 17 is maintained in a very hot condition because of its proximity to the heat-producing unit 6, and because the conductor bar 18 is secured to the plate 17 in contact therewith, said conductor bar will also be maintained in a very hot condition. The conductor bar 18 is in very intimate contact with the tubular element 13 because of the close contact of a portion of the outer face of the tubular element with the wall of the opening 18' formed adjacent to the forward end of the conductor bar, and because of this arrangement heat will be conducted by the plate 17 and the conductor bar 18 to the tubular element 13 whereby said tubular element also will be maintained in a very hot condition. As a result of this situation steam which passes through the tubular element 13 just prior to being discharged from the steam-discharge orifice 2 is superheated so that the steam discharged from the orifice 2 is in a dry, moisture-free condition. An important feature of the invention is that a substantially greater portion of the tubular element 13 is spaced from other portions of the structure of the iron because of the relative small diameter of said tubular element with respect to the diameter of the opening 18'. Thus the opportunity for the heat of the tubular element to be conducted away from said tubular element, and thereby interfere with the maintenance of the tubular element in a hot condition, is reduced to the minimum.

The cap 42 which seals the water inlet 41 is provided, in the portion thereof which is surrounded by the sleeve 43, with a longitudinal opening 42^a that is open at the bottom of the cap. Also, the cap has formed therein a transverse opening 42^b which communicates at its inner end with the opening 42^a and extends through portions of the Bakelite part of the cap and the sleeve thereof, with said transverse opening being open at the outer face of said sleeve. By providing the cap 42 with the openings 42^a and 42^b steam within the reservoir 8 is permitted to bleed from the reservoir when the cap is being unscrewed, whereby a sudden rush of steam from the reservoir is avoided when the cap is removed from the inlet 41.

I claim:

1. A pressing iron comprising a base having a pressing face, a body portion providing a reservoir adapted to receive a body of water, said body portion being disposed above said base, heating means for heating the base of the iron and for heating said body portion so as to convert the water within the reservoir thereof into steam, a steam-discharge orifice formed in said base at a point adjacent to the forward end thereof, a steam conductor for conducting steam produced within said reservoir to said steam-discharge orifice, and heat-conducting means for conducting heat from said heating means to said steam conductor so as to maintain same in such heated condition that steam passing therethrough is superheated, said heat-conducting means comprising an element which has a portion thereof arranged in close proximity to said heating means and another portion arranged in contact with said steam conductor, said element being formed of a material which is characterized by being a better conductor of heat than

the material of which adjacent parts of the pressing iron are formed and the element being out of direct contact with the adjacent portions of the body portion of the pressing iron.

2. A pressing iron comprising a base having a pressing face, a body portion providing a reservoir adapted to receive a body of water, said body portion being supported by said base and being secured thereto, heating means for heating the base of the iron and for heating said body portion so as to convert the water within the reservoir thereof into steam, a steam-discharge orifice formed in said base at a point adjacent to the forward end thereof, a steam conductor for conducting steam produced within said reservoir to said steam-discharge orifice, and heat-conducting means for conducting heat from said heating means to said steam conductor so as to maintain same in such heated condition that steam passing therethrough is superheated, said heat-conducting means comprising an element formed of good heat conducting material which has a portion thereof arranged in close proximity to said heating means and which is provided with an opening formed through another portion thereof through which said steam conductor extends with an outer surface portion of the steam conductor arranged in close contact with the wall of said opening.

3. A pressing iron comprising a base having a pressing face, a body portion providing a reservoir adapted to receive a body of water, said body portion being disposed above said base, heating means for heating the base of the iron and for heating said body portion so as to convert the water within the reservoir thereof into steam, a steam-discharge orifice formed in said base at a point adjacent to the forward end thereof, a steam conductor for conducting steam produced within said reservoir to said steam-discharge orifice, heat-conducting means for conducting heat from said heating means to said steam conductor so as to maintain same in such heated condition that steam passing therethrough is superheated, said heat-conducting means comprising an element formed of good heat conducting material which has a portion thereof arranged in close proximity to said heating means and which is provided with an opening formed through another portion thereof through which said steam conductor extends with an outer surface portion of the steam conductor arranged in close contact with the wall of said opening, and a recess formed in a wall of said body portion in which a portion of said heat-conducting element is disposed.

4. A pressing iron comprising a base having a pressing face, a body portion providing a reservoir adapted to receive a body of water, said body portion being disposed above said base, heating means for heating the base of the iron and for heating said body portion so as to convert the water within the reservoir thereof into steam, a steam-discharge orifice formed in said base at a point adjacent to the forward end thereof, a steam conductor for conducting steam produced within said reservoir to said steam-discharge orifice, and heat conducting means for conducting heat from said heating means to said steam conductor so as to maintain same in such heated condition that steam passing therethrough is superheated, said heat conducting means comprising a plate arranged in close proximity to said heating means, and an element secured to said plate and having a portion ar-

ranged in contact with said steam conductor, said element being formed of a material which is characterized by being a better conductor of heat than the material of which adjacent parts of the pressing iron are formed and the element being out of direct contact with the adjacent portions of the body portion of the pressing iron.

5. A pressing iron comprising a base having a pressing face, a body portion providing a reservoir adapted to receive a body of water, said body portion being disposed above said base, heating means for heating the base of the iron and for heating said body portion so as to convert the water within the reservoir thereof into steam, a steam-discharge orifice formed in said base at a point adjacent to the forward end thereof, a steam conductor for conducting steam produced within said reservoir to said steam-discharge orifice, and heat-conducting means for conducting heat from said heating means to said steam conductor so as to maintain same in such heated condition that steam passing therethrough is superheated, said steam conductor being disposed in an opening formed in said body portion which is of substantially greater diameter than said steam conductor so that a substantial portion of the steam conductor is out of direct contact with said body portion in order to minimize the opportunity for the heat of the steam conductor to be conducted therefrom by 30 spaced from said reservoir of said body portion.

6. A pressing iron comprising a base having a pressing face, a body portion providing a reser-

voir adapted to receive a body of water, the upper portion of said body portion being open, said body portion being supported by said base and being secured thereto, heating means for heating the base of the iron and for heating said body portion so as to convert the water within the reservoir thereof into steam, a steam-discharge orifice formed in said base at a point adjacent to the forward end thereof, said body portion having a solid wall portion in which an elongated opening is formed which is in alignment with respect to said steam-discharge orifice, a tubular steam conductor disposed in said opening, said tubular steam conductor being of substantially less diameter than said elongated opening so that its outer face is spaced from the wall of said elongated opening and the lower end portion of said steam conductor being in screwthreaded engagement with said base at said steam discharge orifice, an inwardly extended flange disposed within said elongated opening, a nut mounted on said steam conductor at the upper end thereof for connecting said steam conductor to said flange, a cover plate for closing the upper portion of said body portion, a steam dome supported by said cover plate through which steam passes from said reservoir to said elongated opening and the steam conductor therein, and heat-conducting means for conducting heat from said heating means to said steam conductor so as to maintain same in such heated condition that steam passing therethrough is superheated.

FRED A. MILLER.
